US0D1099319S

(12) **United States Design Patent** (10) **Patent No.:** **US D1,099,319 S**
(45) **Date of Patent:** **** Oct. 21, 2025**

(54) **BONE PLATE**

(71) Applicant: **Stryker European Operations Limited**, Carrigtwohill (IE)

(72) Inventors: **Tobias Blüchel**, Selzach (CH);
Pierre-Luc Sylvestre, Grenchen (CH)

(73) Assignee: **Stryker European Operations Limited**, Carrigtwohill (IE)

(**) Term: **15 Years**

(21) Appl. No.: **29/946,382**

(22) Filed: **Jun. 7, 2024**

(51) LOC (15) Cl. **24-03**

(52) U.S. Cl.

USPC **D24/155**

(58) **Field of Classification Search**

(57) **CLAIM**

The ornamental design for a bone plate, as shown and described.

DESCRIPTION

FIG. 1 is a front perspective view of a bone plate, showing our new design;

FIG. 2 is a front elevation hereof;

FIG. 3 is a rear elevation view thereof;

FIG. 4 is a right side elevation view thereof;

FIG. 5 is left side elevation view thereof;

FIG. 6 is a top plan view thereof; and,

FIG. 7 is a bottom plan view thereof.

The broken lines depict portions of the bone plate that form no part of the claimed design.

1 Claim, 4 Drawing Sheets
